No. 784,759.

PATENTED MAR. 14, 1905.

O. J. ROUSSEAU & E. C. FERRIS.

GAS ENGINE.

APPLICATION FILED SEPT. 11, 1902.

Fig. 1.

UNITED STATES PATENT OFFICE.

CANFIELD J. ROUSSEAU, OF BRIDGEPORT, AND ELMER C. FERRIS, OF STAMFORD, CONNECTICUT, ASSIGNORS, BY MESNE ASSIGNMENTS, TO UNIVERSAL KEROSENE ENGINE COMPANY, A CORPORATION OF NEW YORK.

GAS-ENGINE.

SPECIFICATION forming part of Letters Patent No. 784,759, dated March 14, 1905.

Application filed September 11, 1902. Serial No. 122,986.

To all whom it may concern:

Be it known that we, CANFIELD J. ROUSSEAU, a subject of the King of Great Britain, and a resident of Bridgeport, and ELMER C. FERRIS, a citizen of the United States, and a resident of Stamford, in the county of Fairfield and State of Connecticut, have invented certain new and useful Improvements in Gas-Engines, of which the following is a specification, taken in connection with the accompanying drawings, which form a part of the same.

This invention relates generally to gas-engines such as are especially adapted for use with liquid hydrocarbons; and it more specifically consists of a device located in the working cylinder of such a gas-engine for vaporizing the liquid hydrocarbon supplied thereto.

In the accompanying drawings, in which the same reference character refers to similar parts in the several figures, Figure 1 is a sectional view showing an embodiment of this invention as applied to a gas-engine. Fig. 2 is a perspective view of the vaporizer. Fig. 3 is a transverse section of the same, taken on the line 3-3 of Fig. 2.

In the embodiment of this invention shown in the drawings, A represents in axial section the working cylinder of a gas-engine, this cylinder being provided with the usual water-jacket A'. This cylinder is provided with an exhaust-port A³ and with the air-inlet port A⁴, which communicates with the working space A² of the cylinder, to which air is supplied through the passage-way A⁵. This passage-way communicates with crank-chamber A⁶, to which air is admitted by inlet-port A⁷. Within this cylinder there operates the piston C' indicated, provided with the suitable upturned flange C near the admission-port A⁴ for the purpose of deflecting the entering charge of inrushing air. This piston is shown in the lowest position and is connected with the usual connecting-rod X and crank-shaft Y, so that it reciprocates within the cylinder, its upper position being

indicated in dotted lines. This piston is also provided with the usual packing C². At the upper end of the cylinder there is secured to the head of the same the igniter B, of usual construction, which is kept suitably heated by the combustion within the cylinder during the normal operation of the engine and serves to ignite the mixed gases within the working cylinder in a well-known manner. It will of course be understood, however, that any other means of igniting these gases may be employed.

This engine is adapted to be operated by liquid hydrocarbons, and these hydrocarbon oils are forced into the working cylinder in suitable charges through the injector D⁴, which is preferably secured in one side of the cylinder. The injector D⁴ is shown as firmly secured upon the cylinder A by the two bolts D⁵ D⁶, and this injector is provided with the check-valve D⁶, forced against a suitable seat D², formed in said injector by the spring D⁷. Charges of oil are forced into this injector at proper times during the operation of the engine by the oil-pump E⁵, the piston E⁴ operating within the cylinder of this pump to draw oil from the supply-pipe E³ past the spring-pressed check-valve E² and operating to force the same at each stroke of the engine past the check-valve E' into the pipe E⁸, which is connected with the pump by the coupling E and which is connected with the injector by the coupling D⁹. The pump piston or plunger E⁴ is lifted a slight distance by the eccentric and eccentric-rod Z at a certain period of each revolution of the engine.

The injector-valve discharges the oil into the vaporizer D, which is clearly indicated in the drawings. This vaporizer comprises a cylindrical body projecting a considerable distance into the working cylinder, preferably in a direction radial to said cylinder, and is preferably formed of brass or other similar material having a high conductivity for heat and a high heat-retaining capacity, so as to readily absorb the heat from the gases within the cylinder and yield the same

up again to the oil when it is forced into said vaporizer. This vaporizer is firmly secured to the injector by the screw-threaded portion D^{10} , which engages a corresponding threaded portion of the injector and firmly forces the shoulder D^{11} of the vaporizer against the injector end, so that the vaporizer assumes the position indicated in Fig. 1. It will be seen that by this means the vaporizer is supported very close to the check-valve D^6 , so that there is very little space for the accumulation of oil at this point. The vaporizer D is formed with the longitudinal capillary passage D' , extending through the same and communicating at the outer end of the vaporizer with a similar transverse capillary passage terminating in the orifice D^{12} , which discharges the vaporized hydrocarbon toward the cylinder-head, and thereby insures its thorough mixture with the compressed air of the charge. It is desirable that the passage in the vaporizer be made of small diameter in order that the oil may be forced into and through the same in the proper manner.

The igniter is heated by any convenient means upon starting up the engine, and the operation of the vaporizer after the engine has been operating sufficiently long to assume its normal working condition is as follows: The vaporizer becomes, through the hot gases in the working cylinder, highly heated, and as the oil is fed into it in definitely-measured charges past the check-valve at each stroke of the engine each charge of oil is instantly distributed along the entire length of the capillary passage D' and through the same, being heated to such an extent by absorption from the relatively large highly-heated metal mass of the vaporizer that at or before the oil emerges from the orifice D^{12} it assumes a vaporized condition and is discharged through this orifice in the form of vapor, at once mixing with the charged air in the cylinder.

When complete compression of the charge forces some of this combustible mixture into the igniter, it explodes and forces the piston downward. In this way very perfect combustion is secured, smoke and noxious gases

in the exhaust are prevented, and the engine is, through the perfect combustion attained, enabled to operate with a very high economy. The complete vaporization of the oil in the vaporizer is due to the highly-heated condition of said vaporizer, it being held continuously in a mass of burning or highly-heated gases, and to the distribution of the charge of oil along the entire length of the fine capillary passage in said vaporizer, whereby said oil is brought in the form of a thinly-attenuated body into immediate contact with the heated metal of the vaporizer.

It is of course understood that many modifications may be made in this device without departing from the spirit of this invention. Those familiar with this art may make variations in the proportions of parts and, furthermore, may substitute different parts for those indicated in the drawings in certain instances. We do not, therefore, desire to be limited to the disclosure herein made in this case; but

What we do claim as new, and what we desire to secure by Letters Patent, is set forth in the appended claims:

1. In a hydrocarbon internal-combustion engine comprising a cylinder and piston reciprocating therein, a vaporizer formed of a capillary tube of heat-retaining material located wholly within the working cylinder. 75

2. In a hydrocarbon internal-combustion engine comprising a cylinder and piston reciprocating therein, a vaporizer formed of a capillary tube of heat-retaining material located wholly within the working cylinder, the discharge end of said tube pointing toward the cylinder-head. 80

3. In a hydrocarbon internal-combustion engine comprising a cylinder and piston reciprocating therein, a vaporizer formed of a capillary tube of heat-retaining material located wholly within the working cylinder and radial thereof. 90
